UNITED STATES PATENT OFFICE.

HENRY S. PALM, OF READING, PENNSYLVANIA.

BODY-ELEVATING MECHANISM FOR DUMPING-WAGONS OR THE LIKE.

1,264,432.

Specification of Letters Patent. Patented Apr. 30, 1918.

Application filed January 22, 1916. Serial No. 73,511.

To all whom it may concern:

Be it known that I, HENRY S. PALM, a citizen of the United States, residing at Reading, in the county of Berks and State of Pennsylvania, have invented certain new and useful Improvements in Body-Elevating Mechanism for Dumping-Wagons or the like, of which the following is a specification.

10 My invention relates particularly to body-elevating apparatus for dumping wagons, and it consists in the improved elevating-lever mechanism and operating means therefor hereinafter fully described in connection 15 with the accompanying drawings, the novel features of which are definitely set forth in the claims.

Figure 1 is a sectional side elevation showing a movable body and a supporting 20 frame therefor, in connection with my improved mechanism as preferably constructed; the body being shown in partially elevated position, but the folded-down position being indicated in dotted-lines.

25 Fig. 2 is a partial plan view of the same with the body removed, the levers on one side being broken away to more clearly show the construction.

Referring to the drawing, which shows a 30 preferred embodiment of my invention, 5, 5, indicate the side members of a supporting frame for the relatively movable body 6 carried thereon. These side members are maintained in their spaced relation by a front 35 cross member 7 and a rear spacing bar 8, and each is formed, as shown, with a forwardly extending guide way 9, near its lower edge. Elevating mechanism for raising the body from its supporting frame is 40 adapted to fold-up within the latter when the body is resting upon the frame, and, when extended to vertically lift the body to a considerable height.

This elevating mechanism, as shown in the 45 drawing, comprises main arms 10, 10, formed of straight bars having their rearward ends pivotally connected at 11, 11, to the rearward ends of the side member 5, 5, near the upper edge thereof, and their forward ends 12, 12, slidably pivoted to the forward end of the body 6 in guide ways 13, 13, provided therefor, said ends being preferably provided with rollers as shown to insure free movement in the guide ways. Midway 55 of the length of the arms 10, 10, are pivotally secured at 14, 14, frame member

arms 15, 15, the free ends of which are slidably engaged in the frame guide ways 9, 9. This construction, as will be readily seen, forms toggle levers for elevating the front 60 of the body 6; the main arms 10, 10, between the pivots 14, 14 and ends 12, 12, forming the body members of the toggles, and the frame arms 15, 15, forming the frame members thereof. The portions of 65 the main arms rearward of the pivots 14, 14, to the end pivots 11, 11, form rigid body extensions of the toggles. When sliding movement is imparted, as hereinafter described, to the ends of the frame arms 15, 15, 70 to move them rearward in their guide ways 9, 9, the toggle levers are extended, swinging on the pivots 11, 11, of the main arms, the ends 12, 12 of said arms moving backward in the guide ways 13, 13, secured to the body, 75 in elevating the latter.

Rear elevating arms 20, 20, also formed of straight bars, are pivotally connected at 21, 21, to the rearward end of the body 6, and their forward ends are slidably engaged 80 in the guide ways 9, 9, of the side members 5, 5. Pivotally connected to these rear arms at 22, 22, midway of their length, are rear frame member arms 23, 23, their free ends being pivoted at 24, 24, to the rear ends of 85 the side members 5, 5, directly below the pivots 11, 11 as shown. This construction forms rear toggle levers, for elevating the rear of the body 6; the arms 20, 20, between the body pivots 21, 21, and the frame member pivots 22, 22, forming the body members of the toggle, and the rear frame arms 23, 23 forming the frame members thereof. The portions of the arms 20, 20, between 90 the pivots 22, 22, and the guide way ends, 95 form rigid body extensions, and when moved rearward in said guide ways 9, 9 extend said toggles to elevate the rear of the body.

As before stated, it is only necessary to 100 slidably move rearward in the guide ways 9, 9, the ends of the arms 15, 15, and 20, 20, both pivotally engaged therein, to extend both the front and rear toggles to vertically elevate the body. Any means for so sliding 105 these toggle actuating ends may be employed, the simple preferred manner, as shown in the drawings, comprising racks 25, 25 having lugs pivotally secured to the ends of the arms 15, 15, and moved longitudinally 110 by pinion gears 26, 26 on crank shaft 27. The shaft 27 may be driven in any well

known manner; and I have indicated a gear wheel 28 outside the supporting frame for conveniently locating a train of driving gears, not shown. Directly below the shaft 5 27 is located a parallel shaft 29, having rollers 30, 30, thereon to support said racks and maintain them in constant mesh with the pinions 26, 26.

The ends of the arms 15, 15 are provided 10 with rollers, as shown, bearing in the guide ways 9, 9, to facilitate the sliding movement of said arms, and I preferably connect the ends of these arms by a shaft 31 to which the lugs of racks 25, 25 are pivoted. A similar shaft 32 connects the ends of the arms 20, 20, which also have rollers bearing in the guide ways 9, 9. The pivotal lugs 33, 33, of the racks 25, 25, are bent upward so as to permit the racks to pass under the shaft 32; and said lugs are preferably provided with spaced shoulders 34, 34, to contact with said shaft 32 and slidably move the arms 20, 20.

As shown in the drawings, the arms 15, 25 15, when in folded down position, extend nearer the front end of the guide ways 9, 9, than the sliding ends of the arms 20, 20, so that the rearward movement of the racks 30 first operate only the front toggles to partially raise the front of the body 6, until the shoulders 34, 34 come into contact with the shaft 32, when the rear toggles begin to extend and raise the rear of the body with the further raising of the front of the same. 35 This construction permits of reducing the strains by elevating only a portion of the load at the start, and at the same time gives a pitch to the body for permitting the ready discharge of its load. This pitch however 40 is determined by the proportions of the toggles and may be varied as desired to suit the requirements.

My invention thus fully described provides a simple and effective elevating mechanism, and one that while it lifts to a great height, folds into a comparatively small space when in lowered position, with nothing depending below the supporting frame, which latter is important as it permits ready 45 application to vehicles, especially motor trucks. I do not desire to limit myself to the specific structure shown and described, but:

What I claim is:

50 1. In combination with a movable body and a supporting frame therefor having its forward portion provided with a horizontal guide-way; separate front and rear toggle-lever connections between said frame and body, the former having its body member extended rearwardly and pivotally connected to the rear portion of the frame and its frame member pivotally connected to said guide-way, and the latter having its 55 body member extended forwardly and

pivotally connected to said guide way, and its frame member pivotally connected to the rear portion of the frame; and means for moving both of said guide-way connections rearwardly to effect the elevation of the 60 body.

2. In combination with a movable body and a supporting frame therefor having its forward portion provided with a horizontal guide-way; separate front and rear toggle-lever connections between said frame and body, the former having its body member extended rearwardly and pivotally connected to the rear portion of the frame and its frame member pivotally connected to said guide way, and the latter having its body member extended forwardly and pivotally connected to said guide way, and its frame member pivotally connected to the rear portion of the frame; and means for moving both of said guide-way connections rearwardly to effect the elevation of the 65 body; said horizontal guide-way being located below the pivotal frame connection of the front toggle-lever body member.

3. In combination with a movable body and a supporting frame therefor having its forward portion provided with a horizontal guide-way; separate front and rear toggle-lever connections between said frame and body, the former having its body member extended rearwardly and pivotally connected to the rear portion of the frame and its frame member pivotally connected to said guide-way, and the latter having its body member extended forwardly and pivotally connected to said guide-way and its frame member pivotally connected to the rear portion of the frame; and operating means comprising a horizontally movable frame member pivotally connected to one of said 70 guide-way connections and adapted to operatively engage the other.

4. In combination with a movable body and a supporting frame therefor having its forward portion provided with a horizontal guide-way; separate front and rear toggle-lever connections between said frame and body, the former having its body member extended rearwardly and pivotally connected to the rear portion of the frame and its frame member pivotally connected to said guide-way, and the latter having its body member extended forwardly and pivotally connected to said guide-way and its frame member pivotally connected to the rear portion of the frame; and operating means comprising a horizontally movable frame member having a pivot lug connected to one of said guide-way connections and adapted to operatively engage the other guide-way connection during a determined portion of its movement.

5. In combination with a movable body and a supporting frame therefor having its

- forward portion provided with a horizontal guide-way; separate front and rear toggle-lever connections between said frame and body, the former having its frame member 5 provided with a pivotal connection to said guide-way, and the latter having its body member extended and provided with a pivotal connection to said guide-way; and operating means comprising a horizontally moving frame member having one end thereof connected to one of said pivotal connections and adapted to engage and disengage the other of said pivotal connections at a determined point in the guide-way.
- 10 6. The combination of a movable body; a supporting frame having its rearward portion provided with an upper pivot-support adjacent the body-supporting top of the frame and with a lower pivot-support, and its forward portion provided with a lower horizontal guide-way; separate front and rear toggle-lever connections between said frame and body, the former having its body member extended in an approximately 15 straight line and pivotally connected to said upper pivot-support and its frame member pivotally connected to said guide-way, and the latter having its body member extended in an approximately straight line and pivotally connected to said guide-way, and its frame member pivotally connected to said lower pivot-support; and an operating gear on said frame comprising a horizontally 20 movable rack pivotally connected to one of said guide-way connections and adapted to operatively engage the other.
- 25 7. The combination of a movable body; a supporting frame having its rearward portion provided with an upper pivot-support adjacent the body-supporting top of the frame and with a lower pivot-support, and its forward portion provided with a lower horizontal guide-way; separate front and rear toggle-lever connections between said frame and body, the former having its body member extended in an approximately straight line and pivotally connected to said upper pivot-support and its frame member pivotally connected to said guide-way, and the latter having its body member extended in an approximately straight line and pivotally connected to said guide-way, and its frame member pivotally connected to said lower pivot-support; and means for moving said guide-way connections horizontally 30 to effect the elevation of the body.
- 35 8. In combination with a movable body and a supporting frame therefor having its forward portion provided with a horizontal guide-way; separate front and rear toggle-lever connections between said frame and body, the former having its body member extended rearwardly and pivotally connected to the rear portion of the frame and its frame member pivotally connected to said guide-way, and the latter having its body member extended forwardly and pivotally connected to said guide-way, and its frame member pivotally connected to the rear portion of the frame; and means for moving both of said guide-way connections rearwardly to effect the elevation of the body; one of said toggle-lever body members having a slidable body connection.

In testimony whereof I affix my signature. 75
HENRY S. PALM.
